GAS BURNER ASSEMBLY

Clarence L. Dewey, Elkhart, Ind., assignor to
 Bendix Aviation Corporation, South Bend, Ind.,
 a corporation of Delaware

Application April 10, 1943, Serial No. 482,539

9 Claims. (Cl. 158—104)

This invention is directed to a gas burner assembly comprising a plurality of individual gas burners carried by a frame or support which makes provision for the mounting of the individual burners and the gas-air ducts leading thereto as well as the centrally disposed pilot light and the flash tubes which radiate from the pilot light to the individual burners.

The object of the present invention is to simplify the general structure by forming the parts thereof mainly from metal stampings, preferably of sheet aluminum, together with gas-air ducts configured from lengths of metal tubing to provide Venturi tubes adapted to afford a proper mixture of gas and air for admission to the burners. The burner heads are preferably formed by a die casting operation, and the parts thus constructed are capable of being assembled and united without the provision of extraneous fastenings which greatly simplifies the operations involved in the making and assembling of the parts into a unified structure adapted for mounting as a unit on a gas stove or the like.

Further objects and details will appear from a description of the invention in conjunction with the accompanying drawings wherein:

Figure 1 is a top plan view of the entire assembly;

Fig. 2 is a sectional view taken on the offset line 2—2 in Fig. 1 looking in the direction of the arrows;

Fig. 3 is a front view of the burner assembly; and

Fig. 4 is a plan view of one of the metal blanks which are bent to tubular formation in the construction of the flash tubes.

The structure as a whole, in the form shown which provides an assembly of four burners, is mounted upon and carried by a rectangular body plate 10 which is provided near its forward edge 11 with a pair of upwardly arched ridges 12 which bridge and fit snugly against the intermediate body portion of a pair of gas-air ducts 13 which underlie the body plate and extend rearwardly to and make connection with a pair of rear burners 14 which stand beyond and in diagonal relation to the rear corners of the body plate.

The ridges 12 extend inwardly in parallel relation to a point below the middle of the body plate at which point the ridge formation on the inner side terminates in the flat surface of the central portion of the body plate which is upwardly stepped at 15, but on the outside the ridge formation continues in each instance as an oblique downwardly stepped offset 16 which terminates in

the edge of the body plate near the rear corner thereof so that the side portions 17 of the body plate will stand in slightly depressed relation to the center portion of the plate.

5 This formation provides a channel socket for each of the rearwardly extending gas-air ducts 13 which diverge throughout their rear portions 18 to follow the contour of the body plate, so that when assembled the body plate will fit snugly over the top of each of the rearwardly extending centrally disposed gas-air ducts to afford a channel socket therefor which permits the parts to be permanently united by spot-welding at the points 19.

10 In order to reinforce the front portion of the body plate, the same is provided with transversely extending outer and inner spaced ribs 20 and 21 which connect the ridges 12 on the inside and combine with ribs 22 and 23 united with the outside of the ridges, to afford a stiff and firm reinforcement for the forward portion of the body plate.

15 At a point beyond the longitudinal center of the plate, but in the transverse center thereof, the plate is provided with four spaced upwardly bulging bosses 24 which afford four intervening grooves 25 for the reception of the inner ends of four radiating flash tubes 26 extending diagonally toward the respective rear burners 14 and toward forward burners 27 standing in adjacent relation to the front corners of the body plate.

20 Fig. 4 is a plan view of one of the metal blanks 28 (Fig. 4) of generally rectangular formation which at one end are concavely cut along their edges on each side at the points 29 which unite in an edge-tapered tip 30.

25 The flash tubes are formed from stamped sheet metal blanks 28 (Fig. 4) of generally rectangular formation which at one end are concavely cut along their edges on each side at the points 29 which unite in an edge-tapered tip 30.

The blank near its forward end is provided with a port 31 and at its opposite end with a tongue 32. The blank in the form above described is bent to the tubular formation of the flash tube 26 with its edges in abutment along a center seam 33 and with the concavely cut edges 29 uniting to form an obliquely upwardly opening discharge aperture 34 which merges into an underlying lip 35 at the tip end.

30 Each of the flash tubes is similarly formed, and when their inner ends are socketed within the grooves 25, the respective tongues 32 will be thrust downwardly through apertures 36 and offset as in Fig. 2 to hook under the bosses, thereby holding the inner ends of the tubes firmly in position and in proximity to a pilot flame emitted from a centrally disposed pilot tube 37 which projects upwardly through a depending cup 38

suspended from the body plate in centrally disposed relation to the bosses 24.

The burners 14 and 27 are of preferably identical construction so that a description of one will suffice for all. Each of the burners is formed in two parts and comprises an upper exterior casing 39 of cylindrical formation and of sheet metal, preferably aluminum, press formed, to the proper configuration to provide a lower flat marginal flange 40 of square outline and a spun-formed upper flared circular throat flange 41.

In order to make provision for the socketing of the inner end of a gas-air tube, the upper burner section on its forward side is outwardly extended to provide a half-collar 42. The upper outer burner section combines with a lower inner section 43 of sheet metal die-formed to provide an upwardly extending inner air duct 44 which at its lower end is outwardly extended to afford the base 45 of an annular channel 46, the base merging into a cylindrical outer wall 47, terminating in a flat marginal flange 48, square in outline, which registers with the flange 40 of the upper section.

Spot-welding points 49 and 50 serve to unite the two flanges 40 and 48 to one another and to unite the burner as a whole to the surface of the body plate, in the case of the forward burners 27 although the rear burners 14 are supported solely by the respective gas-air tubes to which they are attached.

In the case of each of the burners, however, the wall 47 of the lower section is interrupted on the forward side to provide a half-collar 51 which registers with the companion half-collar 42 to afford a circular socket for the reception of the inner end of the gas-air tube which is secured to the socket thus provided, by spot-welding points 52.

In the case of the forward burners 27, the gas-air ducts 53 are relatively short so that the flared or throated intake ends 54 of all four ducts will stand in alignment. In each instance, the flared intake end is in the form of a Venturi tube which contracts to a restricted neck 55 beyond which the tube is tapered to an increasing diameter, and in the case of the rear ducts the tubes continue throughout at the enlarged diameter, in order to afford the necessary length required in conducting the gas-air mixture to the rear burners.

The outer margin of each of the flared intake ends 54 is in the form of a hooked flange 56 which clamps the edge of a fixed shutter plate 57 having radiating air intake ports 58 which are fitted to register in greater or less degree with similar ports 59 in an adjustable rotatable shutter 60 which is rotatably mounted upon a center circular flange 61 outwardly struck from the fixed shutter plate which serves as a mounting therefor, but the shutter does not constitute an essential part of the present invention and need not be described in further detail.

In the deep die pressing of the upper end of the inner air duct 44, the sheet metal will be distended to a closed cup formation, the closed end of which is afterwards cut away to provide the tubular formation shown, and at the upper end the duct is provided with rolled screw threads 62 which engage the threaded neck 63 of a burner head of conventional form, which neck merges into a flared shoulder 64 which connects with a flat body ring 65 terminating in a flared rim 66.

The under surface of the flared rim is provided with a multiplicity of radiating ribs 67 which

make interrupted contact with the upper flared surface of the throat flange 41, thus affording a ring of outer burner ports 68 which combine with inner burner ports 69, drilled through the shoulder 64, thereby making provision for inner and outer rings of flame jets. The burner head is preferably in the form of an aluminum die casting, but the particular arrangement and formation of burner flame ports follows conventional lines, and this portion of the structure is not to be regarded as an essential feature of the present invention.

The outer lips 35 of the flash tubes are entered through the adjacent walls of the upper sections of the respective burners so that the connection thus afforded, in conjunction with the hooked flanges 32 at the inner ends of the flash tubes, affords a firm connection for the parts so that the use of extraneous fastening means is unnecessary, and a gas passage to the flash tube is provided.

The parts in the form described may be very easily configured and readily assembled into a firm and rigid structure and united together by the hooked tongues and spot-welding so that there will be no necessity for the employment of screws, bolts, or like extraneous fastenings which may become easily loosened or corroded during an extended period of use.

The body plate section consists of a single stamping properly configured to provide for the socketing of the gas-air ducts and the flash tubes and suitably reenforced by the ribbing to prevent bending or distortion. The gas-air ducts, of Venturi formation, can be readily configured from lengths of tubing by the method disclosed in the Dewey Patent No. 2,265,723, issued December 9, 1941 which permits a plurality of ducts to be configured from a single length of tubing and afterwards cut into unit sections and fitted with the adjusting shutters for regulating the inflow of air which unites with the gas from a tube entered through the center flange 61 in the case of each of the burners.

The burners themselves are all of identical formation and comprise upper and lower sections which may be readily pressed and spun from sheet metal, preferably aluminum, and afterwards capped by a burner head in the form of a die casting which is screwed into place to afford the rings of burner ports through which the gas-air mixture is discharged. Here again extraneous fastenings are unnecessary, since the sections of the burner are formed to readily unite with one another without additional connections.

The formation of the flash tubes is one which permits the lip at the outer end of each flash tube to project through and into the annular chamber in the burner and at the same time provides an exterior port for the discharge of gas ignited by the pilot light so that the formation affords a port through the lip for the inflow of gas directed inwardly toward the pilot light and for the flash back of the ignited gas to the external discharge port 34 which is located immediately below the outer ring of burner ports. Thus the formation of the flash tube is one which not only permits it to be readily secured and united in position, but also affords a suitable duct for the flash ignition of the gas mixture admitted to the burner head.

Although the invention has been described in full detail as applying to the structure of a four headed burner assembly, it is to be understood that a similar structure, without substantial modification save in details of configuration, might

be similarly employed for an assembly of a different number of burner heads as, for instance, a two burner assembly in which the rear burner heads were omitted, or one having some other number of burner heads radially arranged with respect to the pilot light and individually constructed in the manner heretofore described and connected with a body frame suitably configured within the principles of the present invention to accommodate the desired number of burners, and although the tubular portions of the structure are preferably cylindrical, a variation of such form may be employed.

I claim:

1. In a gas burner assembly the combination of a body plate provided at an interior region with a plurality of upwardly extending separated bosses, affording intervening socket grooves, a pilot burner tube positioned adjacent the bosses, a plurality of ported burners located in spaced relation to the pilot burner tube, gas-air ducts leading to the respective burners and having their intake ends in substantial alignment in front of the forward edge of the body plate, and each of the burners having leading thereto a flash tube having its inner end socketed within one of the grooves adjacent the pilot burner tube and having its outer end entered through the wall of the associated burner and apertured exteriorly of the burner wall at a point sufficiently close to a burner port to flash ignite a gas mixture discharged from the burner.

2. In a gas burner assembly the combination of a body plate of stamped sheet metal provided at an interior region with a plurality of upwardly struck separated bosses, affording intervening socket grooves, a pilot burner tube positioned adjacent the bosses, a plurality of ported burners located in spaced relation to the pilot burner tube, gas-air ducts leading to the respective burners and having their intake ends in substantial alignment in front of the forward edge of the body plate, and each of the burners having leading thereto a flash tube having its inner end socketed within one of the grooves adjacent the pilot burner tube and having its outer end entered through the wall of the associated burner and apertured exteriorly of the burner wall at a point sufficiently close to a burner port to flash ignite a gas mixture discharged from the burner.

3. In a gas burner assembly the combination of a body plate provided at an interior region with a plurality of upwardly extending separated bosses, affording intervening socket grooves, a pilot burner tube positioned adjacent the bosses, a plurality of ported burners located in spaced relation to the pilot burner tube, gas-air ducts leading to the respective burners and having their intake ends in substantial alignment in front of the forward edge of the body plate, the burners occupying varying distances from the forward edge of the body plate, the gas-air duct leading to a more distant burner underlying the body plate and being secured thereto by spot welding, and each of the burners having leading thereto a flash tube having its inner end socketed within one of the grooves adjacent the pilot burner tube and having its outer end entered through the wall of the associated burner and apertured exteriorly of the burner wall at a point sufficiently close to a burner port to flash ignite a gas mixture discharged from the burner.

4. In a gas burner assembly the combination of a body plate of stamped sheet metal provided at

an interior region with a plurality of upwardly struck separated bosses, affording intervening socket grooves, a pilot burner tube positioned adjacent the bosses, a plurality of ported burners located in spaced relation to the pilot burner tube, gas-air ducts leading to the respective burners and having their intake ends in substantial alignment in front of the forward edge of the body plate, the burners occupying varying distances from the forward edge of the body plate, the gas-air duct leading to a more distant burner underlying the body plate and being secured thereto by spot welding, and each of the burners having leading thereto a flash tube having its inner end socketed within one of the grooves adjacent the pilot burner tube and having its outer end entered through the wall of the associated burner and apertured exteriorly of the burner wall at a point sufficiently close to a burner port to flash ignite a gas mixture discharged from the burner.

5. In a gas burner assembly the combination of a body plate of stamped sheet metal provided at an interior region with a plurality of upwardly struck separated bosses, affording intervening socket grooves, a pilot burner tube positioned adjacent the bosses, a plurality of ported burners located in spaced relation to the pilot burner tube, gas-air ducts leading to the respective burners and having their intake ends in substantial alignment in front of the forward edge of the body plate, the burners occupying varying distances from the forward edge of the body plate, the gas-air duct leading to a more distant burner underlying the body plate and being secured thereto by spot welding, the body plate being configured to afford an arching ridge above the gas-air duct for socketing the same, and each of the burners having leading thereto a flash tube having its inner end socketed within one of the grooves adjacent the pilot burner tube and having its outer end entered through the wall of the associated burner and apertured exteriorly of the burner wall at a point sufficiently close to a burner port to flash ignite a gas mixture discharged from the burner.

6. In a gas burner assembly the combination of an apertured body plate of stamped sheet metal having at an intermediate region a pilot burner tube secured below the plate aperture in position to discharge a pilot flame upwardly through the plate, a plurality of separated bosses struck upwardly from the body plate, providing intervening socket grooves adjacent the pilot burner tube, the body plate being configured to afford a pair of spaced arched ridges leading from its forward edge, a pair of gas-air ducts aligned at their forward intake ends and having their intermediate portions socketed within said ridges and secured thereto by spot welding, a pair of ported burners secured to the rear ends of said ducts, a pair of flash tubes having their inner ends socketed within the socket grooves and having their outer ends terminating adjacent the burners at a point sufficiently close to a port thereof to flash ignite a gas mixture discharged from said respective burners.

7. In a gas burner assembly the combination of an apertured body plate of stamped sheet metal having at an intermediate region a pilot burner tube secured below the plate aperture in position to discharge a pilot flame upwardly through the plate, a plurality of separated bosses struck upwardly from the body plate, providing intervening socket grooves adjacent the pilot burner tube,

the body plate being configured to afford a pair of spaced arched ridges defining channel sockets leading from its forward edge, a pair of gas air ducts aligned at their forward intake ends and each having an intermediate portion located within the channel socket of one of said ridges and secured thereto by spot welding, a pair of ported burners secured to the rear ends of said ducts, a pair of flash tubes having their inner ends socketed within the socket grooves and having their outer ends entered through the walls of the associated burners and apertured exteriorly of said walls at a point sufficiently close to a burner port to flash ignite a gas mixture discharged from said respective burners.

8. In a gas burner assembly the combination of an apertured body plate of stamped sheet metal having at an intermediate region a pilot burner tube secured below the plate aperture in position to discharge a pilot flame upwardly through the plate, a plurality of separated bosses struck upwardly from the body plate, providing intervening socket grooves adjacent the pilot burner tube, the body plate being configured to afford a pair of spaced arched ridges defining channel sockets leading from its forward edge, a pair of gas-air ducts aligned at their forward intake ends and each having an intermediate portion located within the channel socket of one of said ridges and secured thereto by spot welding, a pair of rear ported burners secured to the rear ends of said ducts, a pair of flash tubes having their inner ends socketed within the socket grooves and having their outer ends entered through the walls of the associated burners and apertured exteriorly of said walls at points sufficiently close to a burner port to flash ignite a gas mixture discharged from said respective burners, a short forward gas-air duct having its forward intake end in alignment with the intake ends of the first-mentioned gas-air ducts, a forward ported burner into which the gas-air duct is entered, said burner

5 being connected to the forward portion of the body plate, and a flash tube having its inner end socketed within a socket groove in the manner first described and with its outer end associated with the forward burner in the manner first described.

9. In a gas burner assembly the combination of an apertured body plate of stamped sheet metal having at an intermediate region a pilot burner tube secured below the plate aperture in position to discharge a pilot flame upwardly through the plate, a plurality of separated bosses struck upwardly from the body plate, providing intervening socket grooves adjacent the pilot burner tube, the body plate being configured to afford a pair of spaced arched ridges defining channel sockets leading from its forward edge, a pair of gas-air ducts aligned at their forward intake ends and each having an intermediate portion located within the channel socket of one of said ridges and secured thereto by spot welding, a pair of rear ported burners secured to the rear ends of said ducts, a pair of flash tubes having their inner ends socketed within the socket grooves and having their outer ends entered through the walls of the associated burners and apertured exteriorly of said walls at points sufficiently close to a burner port to flash ignite a gas mixture discharged from said respective burners, a short forward gas-air duct having its forward intake end in alignment with the intake ends of the first-mentioned gas-air ducts, a forward ported burner into which the gas-air duct is entered, said burner being connected to the forward portion of the body plate, and a flash tube having its inner end socketed within a socket groove in the manner first described and with its outer end associated with the forward burner in the manner first described.

CLARENCE L. DEWEY.
